UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed June 26, 1923. Serial No. 647,788.

To all whom it may concern:

Be it known that I, JOHN WALDHEIM, a citizen of the United States, residing in Elizabeth, in the county of Union and State 5 of New Jersey, have invented certain new and useful Improvements in Typewriting Machines, of which the following is a specification.

This invention relates to fan-folded type-writing machines of the continuous billing type, in which a composite web is fed around a cylindrical platen, the composite web comprising several plies of work-sheets having successive corresponding forms printed thereon, said plies being sometimes separated from each other and sometimes joined at their side edges to form a fan-folded web, the various plies having carbon-sheets interleaved therebetween which are shiftable 20 lengthwise of the plies from form to form. The invention relates more particularly to means for facilitating relative displacement or shifting of the carbon-sheets and the work-sheets.

The Underwood continuous billing type-writing machine which is adapted for this kind of work employs a cylindrical platen, and in said machine the platen is displaced upwardly from its usual printing position 30 by means of a swing frame, preliminary to shifting of the carbon-sheets, so that that portion of the composite web including the carbon-sheets may be straightened out in order that the carbon-sheets may be readily 35 shifted along the work-sheets to a fresh set of forms. There is also employed in said machine a table extending rearwardly from the platen upon which a carbon-carrier is mounted to travel back and forth over said 40 table towards and away from the platen, said carbon-carrier having the ends of the interleaved carbon-sheets connected thereto, and said carbon-carrier being movable rearwardly by a handle while the work-sheets 45 are drawn upwardly to a suitable gage, after which the platen is again lowered to its typing position, in which position the typed forms may then be severed.

An object of the present invention is to 50 facilitate the relative shifting of the carbon-sheets and the work-sheets without lifting the platen, the platen remaining, in the present invention, always in its usual typing position. To this end, there is provided a 55 table extending rearwardly from the platen,

said table having a carbon-carrier movable thereon towards and away from the platen. The carbon-carrier in the present invention, however, is used to move rearwardly, or, in other words, to withdraw the composite web 60 around the platen to free the leading ends of the carbon-sheets from the platen. To this end, said table comprises two sections, a relatively fixed section secured to the typewriter carriage and traveling therewith, and 65 a pivoted section which may be swung about its pivot to raise its rear end to bring said pivoted section of said table to a plane substantially parallel with the usual rear paper-table of the typewriting machine, so that 70 that portion of the composite web including the carbon-sheets occupies a straightened out position. In swinging up the pivoted portion of said table, the carbon-carrier is also caused to travel upwardly and rearwardly over said table section, this being 75 brought about by means which may comprise a cord or band, one end of which may be secured to the relatively fixed portion of said table, said cord being conducted over a 80 suitable pulley, and the other end of it being secured to the rear of the carbon-carrier, so that as the rear end of the swinging portion of said table is raised the cord becomes 85 stretched, and consequently causes the carbon-carrier to travel upwardly and rearwardly on said swinging table portion, thus causing the work-sheets to be drawn rearwardly with the carbon-sheets, the usual feed-rolls being released during this web- 90 withdrawing operation.

After the carbon-sheets have been freed from the platen, the pivoted portion of said table is retained in its inclined position. The feed-rolls may then be thrown on to 95 grasp the leading edges of the work-sheets. The platen may then be rotated to advance the work-sheets relatively to the carbon-sheets, the extent of forward feed of the work-sheets being determined by a suitable 100 gage at the delivery side of the platen. The pivoted portion of the table may then be lowered, and the composite web may be advanced to bring the leading edges of the work-sheets to a second gage, during which 105 time the leading edges of the carbons are also brought to the printing point, and the bottoms of the typed forms are brought to a suitable knife, by which said typed forms 110 may be severed.

A light spring is provided to take up the slack produced in the carbon-carrier-controlling cord when the pivoted section of the table is swung down from its inclined position. Said cord is provided with an enlargement to serve as a stop to abut against a portion of the relatively fixed section of said table to render said cord effective to draw the carbon-carrier over the pivoted section of said table. The upward and rearward travel of the carbon-carrier is limited by a fixed stop on the pivoted portion of said table. Consequently the cord in its stretched condition, when the carbon-carrier is against said stop, limits the swinging movement of the pivoted portion of said table, or, in other words, establishes its inclined position with reference to the platen.

20 Both sections of said table are supported at their rear ends by suitable rollers secured thereto, said rollers bearing on a rod secured to a frame extending rearwardly from the main frame of the typewriting machine.

25 Other features and advantages will hereinafter appear.

In the accompanying drawings,

Figure 1 is a sectional side view of the machine, and shows the work-sheets in the 30 positions they assume at the conclusion of the typing operation that completes the first work-sheet section.

Figure 2 is a sectional view of a spring-drum used to take up the slack produced 35 in the carbon-carrier-controlling cord.

Figure 3 is a top plan view of the machine.

Figure 4 is a sectional side view similar 40 to Figure 1, except that a section of the work-presenting frame or table has been raised to withdraw the composite web around the platen and free the carbon-sheets therefrom, so that the work-sheets may be advanced separately to transfer the carbon-sheets from the first to the second work-sheet section.

50 Figure 5 is a partial sectional side view, showing the next step in the operation after the step disclosed in Figure 4 when the work-sheets have been advanced to bring the leading edges of the carbon-sheets to position for the second work-sheet section.

Figure 6 is a partial sectional side view 55 similar to Figure 5, and shows both the work-sheets and carbon-sheets advanced, after gaging as in Figure 5, to a position where the completed leading work-sheet sections may be severed from the pack, as shown in dot-and-dash lines in this figure.

60 Mounted on a rail 7 in a typewriter-frame 8 is a movable carriage 9 in which is supported a platen 10, which has feed-rolls 11 and 12 co-operating therewith in the usual manner to feed work-sheets through the machine. Fastened to the rear of the carriage 9 is a rear paper-table 13, and fas-

tened to the top of the carriage 9 and in front of the platen 10 by means of brackets 14 is a front paper-table 15, which carries a gage-bar 16 furnished with gages 17 and 18 and also a web-severing knife 19 which 70 may be adjusted to various positions. Fastened to the rear of the frame 8 is a sub-base 20, which may be furnished with a rear rail 21. Supported in the rear on the rail 21 by means of rollers 22 fastened in brackets 23, and in the front by means of brackets 24 which are fastened to the rear of the carriage, is a sub-frame 25. Depending from the rear of the sub-frame 25 is a bracket 26 which supports a spring-barrel 27, the 80 purpose of which will be disclosed hereinafter.

Near the front of the sub-frame 25 are two upstanding ears 28, to which is movably fastened, by means of pivots 29, a work-presenting frame 30 which may have side members 31, a front cross-member 32 and a rear cross-member 34. Mounted on the side members 31 by means of brackets 35 are rollers 36, which support the work-presenting frame 30 90 upon the rail 21 when the former is in its normal position. Mounted on the rear cross-member 34 between brackets 37 is a sheave-wheel 38. The tops of the side members 31 may be furnished with rails 39, which may be extended beyond the rear cross-member 34, as at 40, to support a paper-guard 41. Paper-guides 42 and 43 may be mounted on the front cross-member 32 and on the paper-guard 41 respectively. A carbon-carrier 44, furnished with a plurality of carbon-holding blades 45, may be mounted by means of rollers 46 to move forwardly and backwardly upon the rails 39. A stop 47 may be placed at the rear of the work-presenting frame 30 100 to limit the backward movement of the carbon-carrier 44. A handle 48 may be mounted to the rear of the pivot 29 on the work-presenting frame 30 for the purpose of raising and lowering it. A suitable cord or belt 110 49, fastened by one end, as at 50, to the spring-barrel 27 and furnished with a stop 51, may be led through an opening 52 in the rear of the sub-frame 25, thence over the sheave 38 and fastened to the rear of the 115 carbon-carrier 44, as at 53.

In operation, the work-presenting frame 30 is first allowed to remain horizontal, as in Figure 1, with the carbon-carrier 44 drawn to the extreme rear by means of the spring-barrel 27 and cord 49. The leading edge of a continuous pack 54, made up of a plurality of superimposed work-sheets 54^a, is taken from a suitable container 55, threaded through a pair of restraining rollers 56, which may be fastened to a suitable supporting table, led over the paper-guard 41, between the carbon-holding blades 45, and is drawn through carbon-sheets 57 until the leading ends of the latter are in proper po- 120 125 130

sition in back of the leading ends of the work-sheets 54^a to transfer the first line of matter that is to be typed upon the first work-sheet section.

- 5 The leading edge of the pack so formed, with the carbon-sheets 57 interleaved between the work-sheets 54^a, is now brought forward and fed underneath the platen 10 through the co-operation of the feed-rolls 11 and 12 until the first line of writing on the first work-sheet section is brought to the printing-point. All of the matter that is to appear on a single work-sheet section is now typed upon the first of those sections, and 15 during this typing operation, as the pack 54 is advanced by line-spacing, the leading edge thereof is led underneath the severing knife 19. The conclusion of the typing operation that completes the first work-sheet 20 section will find the pack 54 in a position similar to that shown in Figure 1. The carbon-carrier 44 will have been advanced forwardly upon the work-presenting frame 30, due to the pull of the carbon-sheets 57 25 against the tension of the spring-drum 27. The operator now grasps the handle 48 in her left hand, draws it forwardly and downwardly, and by so doing swings the work-presenting frame 30 upwardly and forwardly 30 around the pivot 29. When this operation is begun with the left hand, the feed-rolls 11 and 12 are thrown off with the right. In raising the work-presenting frame 30, the cord 49 is drawn from around the spring-drum 27, and through the opening 52 until 35 the stop 51 prohibits any further unwinding. The work-sheets 54^a, together with the carbons 57, having been released from the gripping pressure of the feed-rolls 11 and 40 12 upon the platen 10, and the cord 49 having been stopped from further unwinding, the cord 49 now draws the carbon-carrier 44 toward the rear of the work-presenting 45 frame 30 and carries the carbon-sheets 57 along with it until any further raising of the work-presenting frame 30 is stopped by having the rear of the carbon-carrier 44 come in contact with the stop 47. Simultaneously with the withdrawal of the carbon-sheets 57, the leading ends of the work-sheets 54^a are also withdrawn from around the platen 10 by the raising of the work-presenting frame 30, their trailing ends being held stationary during the raising operation by the clamping action of the rolls 56. Both withdrawals occurring at the same time, the carbon and work sheets retain their respective positions relative to one another. 55 When the work-presenting frame 30 has been raised to the limit, the carbon-sheets 57 will be entirely free of the feed-rolls 11 and 12, but the leading ends of the work-sheets 54^a will still remain in a position where they will be engaged by the feed-roll 60 12 when it is again thrown on. The various parts of the mechanism will now have reached positions similar to those shown in Figure 4. Retaining the work-presenting frame 30 in its raised position with her left hand, the operator throws on the feed-rolls 70 11 and 12 with her right hand, and then, still with her right hand, rotates the platen 10 by turning the platen-knob until the leading ends of the work-sheets 54^a have reached the long leg of the gage 17. While this last-described operation is being performed, the carbon-sheets 57 are restrained from advancing with the work-sheets 54^a by means of the cord 49 attached to the carbon-carrier 44. This operation withdraws the carbons 80 57 from the first work-sheet section entirely, and brings their leading edges to a position for transferring the first line of writing on the second work-sheet section. 85 The work-presenting frame 30 is now lowered to its normal position, which creates a slack in the trailing edge of the pack 54, as shown in Figure 1, and also allows the drum 27 to take up the cord 49. The operator again rotates the platen 10 with her right hand, drawing the pack 54 forward together with the carbon-carrier 44 against the tension of the spring-drum 27, until the leading ends of the work-sheets 54^a touch the long 90 leg of the gage 18. This brings the severing point between the first and second work-sheet sections opposite the cutting edge of the knife 19, and also brings the first line of writing on the second work-sheet section 95 to the printing point, as shown in Figure 6. 100 The completed first work-sheet section may now be severed from the pack 54, and the operation repeated.

Variations may be resorted to within the scope of the invention, and portions of the improvements may be used without others.

Having thus described my invention, I claim:

1. In a typewriting machine, in combination with a movable carriage, feed-rolls to feed a continuous pack or fan-folded web of carbon-interleaved work-sheets divided into work-sheet sections underneath and around a platen, a container for said work-sheets, co-operative restraining members to regulate forward movement of said work-sheets, a sub-base in the rear of said machine, a movable sub-frame supported by said sub-base and said carriage to move with the latter, and a work-presenting frame mounted upon said sub-frame to the rear of said carriage and movable therewith to support said work-sheets, said work-presenting frame being pivoted at one end.

2. In a typewriting machine, in combination with a movable carriage, feed-rolls to feed a continuous pack or fan-folded web of carbon-interleaved work-sheets divided into work-sheet sections underneath and around a platen, a container for said work-

5 sheets, co-operative restraining members to regulate forward movement of said work-sheets, a sub-base which includes a supporting rail, a movable sub-frame supported by
10 said rail and said carriage to move transversely of the machine with the latter, and a work-presenting frame mounted near the front end and upon said sub-frame and supported at its rear end upon said rail, said
15 work-presenting frame being pivoted at its front end.

3. In a typewriting machine, in combination with a movable carriage, feed-rolls to feed a continuous pack or fan-folded web of
15 carbon-interleaved work-sheets divided into work-sheet sections underneath and around a platen, a container for said work-sheets, co-operative restraining rollers to regulate the forward movement of said work-sheets, a
20 sub-base which includes a supporting rail fastened to the rear of said machine, a movable sub-frame fitted with rollers in the rear to run upon said rail and fastened to said carriage in the front to move transversely of the machine with the latter, and a work-presenting frame pivoted near its front end upon said sub-frame and supported upon said rail by means of rollers mounted near its rear end, said work-presenting frame being provided with a lever near its forward end.

4. In a typewriting machine, in combination with a movable carriage, a platen and feed-roll mechanism, a work-presenting frame mounted at its front end to the rear of said carriage to swing upwardly and forwardly and which supports the superimposed work-sheets of a continuous pack or fan-folded web, a paper-guard mounted upon the rear of said work-presenting frame, a carbon-carrier movably mounted upon said work-presenting frame and furnished with a plurality of blades for holding carbon-sheets to be interleaved between said work-sheets, and a retracting member fastened by one end to said sub-frame, then led through an opening in the back of said sub-frame, then over the back of said work-presenting frame, and underneath said paper-guard, and fastened to the back of said carbon-carrier to draw it back to the rear of said work-presenting frame.

5. In a typewriting machine, in combination with a movable carriage, a platen and feed-roll mechanism, a movable sub-frame fastened to said carriage to move transversely of the machine therewith, a work-presenting frame mounted near the front end and upon said sub-frame to swing upwardly and forwardly and which supports the superimposed work-sheets of a continuous pack or fan-folded web, a paper-guard mounted upon the rear of said work-presenting frame, a carbon-carrier movably mounted upon said work-presenting frame and

furnished with a plurality of blades for holding carbon-sheets to be interleaved between said work-sheets, and a retracting member fastened by one end to said sub-frame, then led through an opening in the back of said sub-frame, then over a sheave in the back of said work-presenting frame, and underneath said paper-guard, and fastened to the back of said carbon-carrier to draw it back to the rear of said work-presenting frame. 75

6. In a typewriting machine, in combination with a movable carriage, a platen and feed-roll mechanism, a sub-base which includes a supporting rail, a movable sub-frame supported by said rail and said carriage to move transversely of the machine with the latter, a work-presenting frame mounted near the front end and upon said sub-frame to swing upwardly and forwardly, 80 and supported at its rear end upon said rail, and which supports the superimposed work-sheets of a continuous pack or fan-folded web, a paper-guard mounted upon the rear of said work-presenting frame, a carbon-carrier movably mounted upon said work-presenting frame and furnished with a plurality of blades for holding carbon-sheets to be interleaved between said work-sheets, and a retracting member fastened by one 85 end to said sub-frame, then led through an opening in the back of said sub-frame, then over a sheave in the back of said work-presenting frame, and underneath said paper-guard, and fastened to the back of said carbon-carrier to draw it back to the rear of said work-presenting frame. 90

7. In a typewriting machine, in combination with a movable carriage, a platen and feed-roll mechanism, a sub-base which includes a supporting rail, a movable sub-frame supported by rollers upon said rail and fastened to said carriage to move transversely of the machine with the latter, a work-presenting frame mounted near the front end and upon said sub-frame to swing upwardly and forwardly and supported at its rear end by rollers upon said rail and which supports the superimposed work-sheets of a continuous pack or fan-folded web, a paper-guard mounted upon the rear of said work-presenting frame, a carbon-carrier movably mounted upon said work-presenting frame and furnished with a plurality of blades for holding carbon-sheets to be interleaved between said work-sheets, a 105 spring-drum mounted near the rear of said sub-frame, and a retracting member fastened by one end to said spring-drum, then led through an opening in the back of said sub-frame, then over a sheave in the back of said work-presenting frame, and underneath said paper-guard, and fastened to the back of said carbon-carrier to draw it back to the rear of said work-presenting frame. 110

120 8. In a typewriting machine, in combination with a movable carriage, a platen and feed-roll mechanism, a movable sub-frame fastened to said carriage to move transversely of the machine therewith, a work-presenting frame mounted near the front end and upon said sub-frame to swing upwardly and forwardly and which supports the superimposed work-sheets of a continuous pack or fan-folded web, a paper-guard mounted upon the rear of said work-presenting frame, a carbon-carrier movably mounted upon said work-presenting frame and furnished with a plurality of blades for holding carbon-sheets to be interleaved between said work-sheets, a 125 spring-drum mounted near the rear of said sub-frame, and a retracting member fastened by one end to said spring-drum, then led through an opening in the back of said sub-frame, then over a sheave in the back of said work-presenting frame, and underneath said paper-guard, and fastened to the back of said carbon-carrier to draw it back to the rear of said work-presenting frame. 130

8. In a typewriting machine, in combination with a movable carriage, a platen and feed-roll mechanism, a sub-base which includes a supporting rail, a movable sub-frame supported by said rail and said carriage to move transversely of the machine with the latter, a work-presenting frame mounted near the front end and upon said sub-frame to swing upwardly and forwardly and supported at its rear end upon said rail, and which supports the superimposed work-sheets of a continuous pack or fan-folded web, a paper-guard mounted upon the rear of said work-presenting frame, a carbon-carrier movably mounted upon said work-presenting frame and furnished with a plurality of blades for holding carbon-sheets to be interleaved between said work-sheets, a spring-drum mounted near the rear of said sub-frame, and a retracting member furnished with a stop and fastened by one end to said spring-drum, then led through an opening in the back of said sub-frame, then over a sheave in the back of said work-presenting frame, and underneath said paper-guard, and fastened to the back of said carbon-carrier, said stop on said retracting member coming in contact with the edge of said opening in said sub-frame when said work-presenting frame is being raised to withdraw said work-sheets at the conclusion of a typing operation that completes a work-sheet section.
9. In a typewriting machine, in combination with a movable carriage, feed-roll mechanism to co-operate with a platen in feeding the superimposed, carbon-interleaved work-sheets of a continuous pack or fan-folded web through said machine, a work-presenting frame pivoted near the rear of said carriage, and movable therewith, and over which said pack or web may be led, a carbon-carrier movably mounted upon said work-presenting frame and furnished with a plurality of blades to which said carbons may be attached, and a retracting member secured at one end, passing over the end of said work-presenting frame, and fastened by the other end to said carbon-carrier to draw it back to the rear of said work-presenting frame whenever said work-presenting frame is raised about its pivot to withdraw said work-sheets.
10. In a typewriting machine, in combination with a movable carriage, feed-roll mechanism to co-operate with a platen in feeding the superimposed, carbon-interleaved work-sheets of a continuous pack or fan-folded web through said machine, a movable sub-frame fastened to said carriage to move transversely of the machine therewith, a work-presenting frame pivoted to said sub-frame near the rear of said carriage, and movable therewith, and over which said pack or web may be led, a carbon-carrier movably mounted upon said work-presenting frame and furnished with a plurality of blades to which said carbons may be attached, a spring-drum mounted near the rear of said sub-frame, and a retracting member furnished with a stop and secured at one end to said spring-drum, then pass-
- bon-carrier movably mounted upon said work-presenting frame and furnished with a plurality of blades to which said carbons may be attached, a spring-drum mounted near the rear of said sub-frame, and a retracting member secured at one end to said spring-drum, then passing through an opening in the end of said sub-frame, then over the back of said work-presenting frame, and fastened by the other end to said carbon-carrier to draw it back to the rear of said work-presenting frame whenever said work-presenting frame is raised about its pivot.
11. In a typewriting machine, in combination with a movable carriage, feed-roll mechanism to co-operate with a platen in feeding the superimposed, carbon-interleaved work-sheets of a continuous pack or fan-folded web through said machine, a sub-base which includes a supporting rail, a movable sub-frame supported by said rail and said carriage to move transversely of the machine with the latter, a work-presenting frame pivoted upon said sub-frame near the rear of said carriage, and movable therewith, and over which said pack or web may be led, a carbon-carrier movably mounted upon said work-presenting frame and furnished with a plurality of blades to which said carbons may be attached, a spring-drum mounted near the rear of said sub-frame, and a retracting member furnished with a stop and secured at one end to said spring-drum, then passing through an opening in the end of said sub-frame, then over the back of said work-presenting frame, and fastened by the other end to said carbon-carrier, said stop upon said retracting member, co-operating with a carbon-carrier stop to limit the raising of said work-presenting frame.
12. In a typewriting machine, in combination with a movable carriage, feed-roll mechanism to co-operate with a platen in feeding superimposed, carbon-interleaved work-sheets of a continuous pack or fan-folded web through said machine, a sub-base which includes a supporting rail, a movable sub-frame supported in the rear by rollers upon said rail, and in the front by said carriage, to move transversely of the machine with the latter, a work-presenting frame pivoted at its front end near the front of said sub-frame to be movable with said carriage, and supported at its rear end by rollers upon said rail, and over which said pack or web may be led, a carbon-carrier movably mounted upon said work-presenting frame and furnished with a plurality of blades to which said carbons may be attached, a spring-drum mounted near the rear of said sub-frame, and a retracting member furnished with a stop and secured at one end to said spring-drum, then pass-

ing through an opening in the end of said sub-frame, then over the back of said work-presenting frame, and fastened by the other end to said carbon-carrier to draw it back 5 to the rear of said work-presenting frame, said stop upon said retracting member coming in contact with the edge of said opening in said sub-frame, and co-operating with a carbon-carrier to stop upon said work-presenting frame to limit the raising of the latter.

13. In a typewriting machine, in combination with a movable carriage, feed-rolls to feed a continuous pack or fan-folded web of 15 carbon-interleaved work-sheets underneath and around a platen, and a forwardly and upwardly swingable work-presenting frame movable with said carriage to support said work-sheets, said work-presenting frame 20 used to straighten out the fan-folded web when it is swung to the limit of its upward and forward movement, and means for automatically retracting the carbons coincidentally with the swinging movement of 25 said work-presenting frame.

14. In a typewriting machine, in combination with a movable carriage, feed-rolls to feed a continuous pack or fan-folded web of carbon-interleaved work-sheets underneath 30 and around a platen, and a forwardly and upwardly swingable work-presenting frame movable with said carriage to support said work-sheets, said work-presenting frame used to straighten out the fan-folded web 35 when it is swung to the limit of its upward and forward movement, and spring-controlled means for automatically retracting the carbons coincidentally with the swinging movement of said work-presenting 40 frame.

15. In a continuous billing typewriting machine, the combination of a carriage, a platen on said carriage around which a composite web, comprising plies of work-sheets 45 with interleaved carbon-sheets, may be fed, and means to facilitate conditioning said web so that there may be a relative shifting between the carbon-sheets and the work-sheets, said means comprising a table over 50 which the web is conducted, said table comprising a relatively fixed section and a swingable section.

16. In a continuous billing typewriting machine, the combination of a carriage, a platen on said carriage around which a composite web, comprising plies of work-sheets 55 with interleaved carbon-sheets, may be fed, and means to withdraw the web around the platen to free the carbon-sheets from said 60 platen and bring that portion of the web including the carbon-sheets to a straightened-out position so that there may be a relative shifting between the carbon-sheets and the work-sheets, said means comprising 65 a table at the rear of the carriage, over

which the web is conducted, said table comprising a relatively fixed section and a movable section.

17. In a continuous billing typewriting machine, the combination of a carriage, a platen on said carriage around which a composite web, comprising plies of work-sheets with interleaved carbon-sheets, may be fed, a straight extension pivoted on said carriage, over which said web is conducted, a carbon-carrier on said extension, to which the ends of the carbon-sheets are attached, means to swing said extension to an inclined position, and means to cause said carbon-carrier to travel rearwardly on said extension during the upward swinging of said extension, to withdraw the web around the platen to free the carbon-sheets from said platen so that there may be accomplished a relative shifting between the carbon-sheets and the work-sheets.

18. In a continuous billing typewriting machine, the combination of a carriage, a platen on said carriage around which a composite web, comprising plies of work-sheets with interleaved carbon-sheets, may be fed, a table at the rear of said carriage, over which the web is conducted towards the platen, said table comprising a relatively fixed section secured to said carriage and a pivoted section supported by said fixed section, a carbon-carrier, to which the carbon-sheets are attached, on said pivoted section, means to move the carbon-carrier rearwardly on said pivoted section to withdraw the web around said platen to free the carbon-sheets from said platen, and means to swing said pivoted section to an abnormal position to straighten out that portion of the web including the carbon-sheets, so that there may be accomplished a shifting of the work-sheets relatively to the carbon-sheets, the rearward movement of the carbon-carrier being caused simultaneously with the swinging movement of said pivoted section, the means for moving said carbon-carrier comprising a cord having one end connected to the rear of said fixed section, said cord being conducted over the rear end of said swinging section, and the other end of said cord being attached to the carbon-carrier.

19. In a continuous billing typewriting machine, the combination of a carriage, a platen on said carriage around which a composite web, comprising plies of work-sheets with interleaved carbon-sheets, may be fed, a table at the rear of said carriage, over which the web is conducted towards the platen, said table comprising a relatively fixed section secured to said carriage and a pivoted section supported by said fixed section, a carbon-carrier, to which the carbon-sheets are attached, on said table, means to move the carbon-carrier rearwardly on said pivoted section to withdraw the web

around said platen to free the carbon-sheets from said platen, means to swing said pivoted section to an abnormal position to straighten out that portion of the web including the carbon-sheets, so that there may be accomplished a shifting of the work-sheets relatively to the carbon-sheets, the rearward movement of the carbon-carrier being caused simultaneously with the swinging movement of said pivoted section, the means for moving said carbon-carrier comprising a cord having one end connected to the rear of said fixed section, said cord being conducted over the rear end of said swinging section, and the other end of said cord being attached to the carbon-carrier, a pulley at the rear end of said swinging section, over which the cord passes, a spring to take up the slack produced in the cord during a downward swing of the pivoted sec-

tion, and a stop to limit the letting-out of the cord during the upward swing of said pivoted section.

20. In a typewriting machine, the combination of a carriage, a platen on said carriage around which a continuous work-web may be fed, a table at the rear of said carriage and connected to travel therewith, over which the web may be conducted to the platen, said table being composed of two sections, namely, a relatively fixed section secured to the carriage and a swingable section pivotally mounted on said carriage, a handle to swing the pivoted section upwardly and forwardly, a fixed guide-rail at the rear of said machine, and rollers on said table-sections to run on said rail to support the rear end of said table.

JOHN WALDHEIM.
